UNITED STATES PATENT OFFICE.

MICHAEL B. GROVE, OF SHELDON, MISSOURI.

FENCE-POST.

SPECIFICATION forming part of Letters Patent No. 394,973, dated December 25, 1888.

Application filed August 21, 1888. Serial No. 283,376. (No model.)

To all whom it may concern:

Be it known that I, MICHAEL B. GROVE, a citizen of the United States, residing at Sheldon, in the county of Vernon and State of Missouri, have invented certain new and useful Improvements in Fence-Posts, of which the following is a specification, reference being had therein to the accompanying drawings.

10 My invention relates to an improvement in fence-posts; and it consists in the peculiar construction and arrangement of parts, more fully hereinafter described, and definitely pointed out in the claim.

15 The object of my invention is to provide a fence-post for barbed-wire, which will dispense with the use of staples or nails and admit of an easy and quick adjustment of the wires in a manner which will permit of their being 20 connected and disconnected with the post with but little trouble.

A further object of my invention is to provide a post for barb-wire which will be strong and durable, admitting of a ready insertion 25 in the ground, and cheaply manufactured.

I attain these objects by the device illustrated in the accompanying drawings, wherein like letters of reference indicate corresponding parts in the several views, and in which—

30 Figure 1 is a side elevation of a post; Fig. 2, a similar view of the reverse side of the post with the slide attached, and Fig. 3 is an edge elevation showing the wings or flanges.

In the drawings, A represents a flat metal- 35 lic post having a pointed lower end, a, a broad base, a', and a tapering upper end, a².

This post is constructed of a single strip of flat metal of uniform thickness throughout its entire length. Circular apertures A' are 40 made at intervals through the metal of the upper portion of the post at points a short distance from the edge thereof. Leading into these apertures, at a point back of their centers, are downwardly-inclined grooves or chan- 45 nels b, which extend to the outside of the edge of the post.

C represents a flat metal bar or slide, the thickness of which corresponds to the thickness of the post. This bar is removably and 50 adjustably secured to the side of the post, its outer edge coming flush with the edge thereof,

while its inner edge occupies a position at the center of the post.

The bar C has an elongated slot, c, cut in its upper end, and a bifurcation or groove, c', 55 formed in its lower end, through which pass bolts or pins D D', provided with nuts, their inner ends being secured to the post. The formation of this slot and groove admits of the bar C being moved up and down, the nuts 60 on the ends of the bolts retaining the bar in its adjusted position, while the groove admits of a quick detachment of the bar by loosening only one nut. A series of apertures, d, are made through the metal of bar C at 65 points registering with the apertures in the post when the bar is in its lowered position.

The front edge of the bar C is indented with a series of enlarged upwardly-inclined grooves or channels, d', which lead into said 70 apertures, thus forming downwardly-extending fingers or tongues d² along the edge of said bar. These fingers d² are so arranged that when the bar is moved up they will come above the mouth of the grooves in the post, 75 thus opening the said grooves and admitting the wire to be inserted therein.

It will be seen by this construction of post, its width being slight, that it would be unable to withstand any pressure placed on its edges 80 and remain solidly vertical in the earth. To overcome this and add to the general efficiency of the post, I place lateral wings or flanges E on each side of the post at its enlarged portion, they being made integral with the said 85 post. The lower edges of the wings E are tapered or inclined to their lower ends, said edges being sharp, while the upper edges are curved inwardly or recessed from their upper points to their outer central edges, and are 90 preferably blunt. This construction admits of the post being readily inserted and rigidly held in place, the upper curved edge of the wings preventing the same from being easily withdrawn.

95 By forming the post of flat metal and arranging the bar on its side a strong, rigid, and light post is formed. The openings in the post and bar registering with each other, the wire is permitted to pass freely through, thus 100 preventing any binding or clamping of the same, which in posts of a somewhat similar

nature has heretofore been an objection, they injuring the wire.

To secure the wires in my improved post, it is only necessary to raise the slide or bar, thus 5 opening the channels in the post, the entire channel and opening or aperture being exposed, owing to the enlarged channels in the bar. The wires are then placed in the openings in the post and the bar allowed to slide 10 down, thus retaining the wires in position.

Having thus described my invention, what I claim as new is—

A fence-post consisting of a single straight and flat piece of metal having apertures and 15 channels leading into the same formed therein, a slide on the side of the post, having

apertures and channels leading into the same formed therein, registering with said other apertures, said slide also having an elongated slot formed in its upper end and an elongated 20 groove formed in its lower end, bolts secured to the post and extending through said slot and groove, respectively, and flanges, as E, projecting laterally from the lower part of the post, substantially as described. 25

In testimony whereof I affix my signature in presence of two witnesses.

MICHAEL B. GROVE.
